1759X

Z. Phinney,
Washing-Machine Pounder,
Patented JUNE 19, 1812.

Jona Whitney
Litter's Patent

1759X

The schedule referred to in this Litter's Patent and making part of the same, containing a description in the words of the said Jona Whitney himself of his Washing and Cleaning Machine.

1st. Any kind of Hockets, with any kind of slats or rounds, or with slats or cogs, to work either in a circular trough or a flat bottomed box, which box may be a convenient Wash Tub, when the rockets are not set in.

2nd. On each Rocket is fastened a perpendicular piece of Board or Plank on which a weight is placed at such a distance from the Rocket as would be the centre of the circumference of the Rocket continued to a circle, through which boards at the centre passes a gudgeon or pin into a roller, which constitutes the weight, this to be placed in a round or flat bottomed box by a handle in the centre of the roller or weight, or with arms on each side of the box, in order to fit a purchase from a roller at the top, the arms from the roller to be extended to pins between the roller or weight and the Rocket. These rockets may be placed in a circular bottomed trough or box by the merely making the rockets more curved and placing the same way as above mentioned.

These rockets will be applied to the breaking of flax or hemp with suitable Mattocks to mesh in with other slats set in a frame below to be worked by means of a Horse or by water with the addition of a crank similar to a saw mill crank. It also may be applied and used as a Cheesecloth.
